JACK

Charles J. Smith, Dayton, Ohio, assignor to The
Dayton Malleable Iron Company, Dayton, Ohio,
a corporation of Ohio

Application December 3, 1935, Serial No. 52,669

4 Claims. (Cl. 254—100)

This invention relates to jacks, and more particularly to jacks adapted for engagement with the bumper or other portions of an automobile or the like.

5 One of the principal objects of the invention is the provision of a reliable yet inexpensive jack that is quickly adjustable for use within a wide range of lifting positions and that, although compact, affords an extended range of lifting travel.

10 Another object of the invention is the provision of such a jack incorporating a load supporting member that is slidably adjustable with respect to the lifting structure and that is arranged to frictionally grip the lifting structure in any de-15 sired position upon application of a load thereto.

15 A further object of the invention is the provision of a simple and compact jack incorporating a lifting screw and a telescopically related sleeve in threaded engagement; the sleeve serving as a means of adjustably receiving the load supporting device of the jack, as a means of increasing the effective length of the lifting screw, and as an enclosure for the screw in the collapsed position of the jack.

20 Other objects and advantages of the invention will be apparent from the following description, the accompanying drawing, and the appended claims.

25 In the drawing which illustrates a preferred embodiment of the invention,—

30 Fig. 1 is a vertical sectional view of a jack constructed in accordance with this invention;

35 Fig. 2 is a fragmentary elevational view looking toward the lower end of the lifting screw;

Fig. 3 is a plan view of the load supporting member;

Fig. 4 is a sectional view as indicated by the line 4—4 of Fig. 3; and

40 Fig. 5 is a fragmentary vertical sectional view as indicated by the line 5—5 of Fig. 1.

The drawing, in which like characters of reference designate like parts throughout the several views thereof, illustrates a jack which is particularly applicable for use for attachment to the frame portion of an automobile such, for example, as the bumper bar or like fitting, in order to elevate the automobile an amount sufficient to enable a tire to be changed. Jacks of this character are required to have an extended lift because of the yielding spring connection between the automobile wheel and the point of application of the jack and because of the general use of large section tires. For these reasons the jack must lift a considerable distance before

the wheel will clear the ground. A jack, to be satisfactory for such service must have a wide range of lifting positions and an extended range of lifting travel as well. In the jack of this invention these qualifications are incorporated in 5 a structure of compact form.

As shown, the jack comprises a base structure 10 upon which is rotatably mounted an upstanding screw shaft 12 of which the major portion is threaded as indicated at 13. The base structure 10 comprises complementary housing portions 15 and 16 which, as shown, have vertical abutting faces and are joined by rivets or bolts as indicated at 18. The assembled portions 15 and 16 provide a hollow housing for support and 15 guidance of the rotatable screw 12 and serve additionally as an enclosure for driving mechanism 19 by which the screw is rotated.

The lower portion of the screw 12, below the threaded portion 13, is shown as having an annular groove 20 formed therein. Below this groove the screw shaft is reduced to form an end portion 21 which is of non-circular contour and provides for driving engagement of the driving means by which the screw is rotated. The extreme lower end of the screw is formed as a convex face as indicated at 22 and is received within the axial depression 23 of a member 24 that projects upwardly from and is attached to the ground engaging part 25 of the base structure. As shown, the member 24 serves as an 20 upstanding projection within the base housing and is formed with a circular peripheral face 27 for support of the screw driving mechanism. The member 24 is held in place through provision of an integral depending lug 28 that is flared outwardly at the lower end as indicated at 29, and which is closely received within aligned openings 30 provided at the junction of the assembled housing portions. 35

In addition to the support afforded the screw by engagement with the base projection, the screw is additionally guided by the upstanding portions of the base housing parts as indicated at 32. As shown, the housing portions 32 flare 45 outwardly and afford sufficient clearance with respect to the screw that it may have a slight angular movement to accommodate a base positioning such as would occur when resting upon uneven or inclined surfaces.

50 Means are preferably provided whereby the screw and base structure are held in interengaged relationship although such means may be omitted if it is desired to provide for convenient separation of the base portion from the 55

5 screw. As shown, the housing portions 32, at a point below the upper ends thereof, have inwardly projecting lugs 33 that are adapted to interengage the annular groove 20 of the screw. If desired, a suitable yielding structure such as 10 spring pressed detent means may be substituted for the lugs 33.

10 The driving mechanism 19 which serves to rotate the screw 12 and impart lifting movement to the jack comprises a gear 35 having an opening 36 toward one end of the hub which conforms in contour to the screw projection 21 and is adapted for loose driving engagement therewith, the interfit of these parts being such that 15 the screw may move angularly within the clearance afforded at the opening of the housing portions 32. The lower portion of the hub of the gear 35 has an axial opening 37 which is a running fit on the periphery of the upstanding member 24. The rotatable gear 35 has meshing engagement with a pinion 38 which is formed on the inner end of a rotatable sleeve 39 that is journaled in the housing portions. The upper end 20 of the sleeve 39 is suitably socketed as indicated at 40 for the reception of a crank handle or the like for operating the driving device.

25 The lifting action of the jack obtains through the medium of a sleeve 42 which is of a length somewhat shorter than the screw but commensurate with its threaded portion, and which has threaded engagement therewith. As shown, the sleeve 42 is constructed of a tubular portion 43 which, at its lower end, has affixed thereto a collar 44 comprising a threaded portion 45 that 30 engages the screw and an upper sleeve like part 46 which telescopically receives the sleeve 42 and is suitably maintained in driving relationship therewith.

35 The sleeve 42 adjustably carries a load supporting member 50 which is shown as comprising a ring-like portion 51 having at one side a lateral projection 52 from which three upstanding laterally staggered pins or fingers 53 project. The pins 53 are conical and taper upwardly from a 40 maximum diameter at the lower portion thereof. These pins are laterally staggered, as indicated, so that they will have a wedging engagement with spaced points on opposite sides of the bottom of the lifted object such as the bumper bar which 45 is indicated by the numeral 55.

50 The ring-like portion 51 of the load supporting member is of a diameter sufficiently large that when held so that the axes of the ring and the sleeve coincide the supporting member may freely 55 slide to any position upon the sleeve 42. The ring and sleeve diameters are so coordinated to permit inclination of the ring-like portion to an engagement with the sleeve such that a downwardly acting load at the load engaging pins will 60 cause the load supporting member to frictionally grip the sleeve and to be maintained thereon in fixed engagement. As shown, this gripping engagement obtains through contact with the sleeve of a ring face 57 which is preferably somewhat 65 less in width than the thickness of the ring-like part 51. It is to be noted that the axes of the staggered pins 53 are parallel and are inclined with respect to the axis of the ring portion 51; the relationship being such that with the load 70 supporting member in holding position on the sleeve the pin axes and sleeve axis are substantially parallel and upright.

75 Although suitable gripping engagement may obtain by frictional contact of the ring face with a rather smooth sleeve surface, the gripping en-

gagement is preferably made more positive by providing a roughened surface on the sleeve as through provision of a shallow spiral thread thereon, or by knurling the surface, as indicated at 58. In order to prevent accidental displacement of the load supporting member in the interval that the jack is being prepared for application to an object, suitable detent means may be provided to yieldingly hold the member 50 in desired position upon the sleeve. As shown, one side of the ring 51 is drilled as indicated at 60 to receive a spring 61 and ball 62 which function as a frictional detent having sufficient holding force to yieldingly maintain the load supporting member in a desired position. Upon assembly 15 of the spring and ball the open end of the drilled hole may be peened over an amount sufficient to prevent removal of the detent parts.

20 A plug cap 63 serves as a closure for the upper end of the sleeve 42. If desired, the cap may have a diameter somewhat larger than shown to serve as a convenient means for rotating the sleeve by hand upon the screw 12.

25 It is thought that it will now be readily apparent that a jack constructed in accordance with the present invention will afford a range of travel such as is required of jacks of that character which are attachable to the frame portion or bumper bar of an automobile. It is further pointed out that this desirable result is obtained 30 in a jack having a collapsed height considerably less than the extreme limit of lifting that may be obtained, in that the screw length is considerably less than the overall length with the sleeve extended and with the load supporting member 35 positioned adjacent the upper end of the screw. A wide range of load supporting positions are afforded and a desired lifting position is readily obtained by merely sliding the load supporting member along the sleeve to a desired location. 40 Application of a load at any position of the load supporting member securely locks the member to the sleeve so that lifting movement may occur at any point within the length of the sleeve. In addition to providing a compact structure in the 45 telescoped position of the sleeve further advantages obtain in that the screw threads may be enclosed by the sleeve to thus prevent damage thereto and to permit the retention of lubricant thereon. Moreover the weight of the jack is comparatively small, as the housing is very short and 50 of small size.

55 While the form of apparatus herein described constitutes a preferred embodiment of the invention, it is to be understood that the invention is not limited to this precise form of apparatus, and that changes may be made therein without departing from the scope of the invention which is 55 defined in the appended claims.

60 What is claimed is:

1. A jack of the character described comprising a base, an upstanding threaded screw rotatably supported in said base and having a comparatively small fractional part of its length within said base, means in said base for rotating said screw, a sleeve telescopically related to and having threaded engagement with said upstanding screw and provided above the top of said base throughout substantially the entire lifting range of said sleeve, said sleeve having a length commensurate with that of the screw and adapted when fully engaged therewith to substantially enclose said screw, load supporting means on the sleeve for engagement with an object to be lifted, said load supporting means comprising a 70 75

ring-like member rockable on the sleeve from a position in which the ring and sleeve axes coincide and in which the ring is slideable thereon to an inclined position in which the ring frictionally grips the sleeve and is fixedly held thereto by the load.

5. 2. In a jack, a vertically movable member, means for moving said member vertically, load supporting means movable on said member for engagement with an object to be lifted comprising a plurality of laterally staggered upstanding conical fingers adapted to simultaneously engage spaced points on opposite sides of the bottom edge of an object in wedging contact therewith.

10. 15. 3. A jack of the character described comprising a base, an upstanding threaded screw rotatably supported in said base, a sleeve telescopically related to and having threaded engagement with said upstanding screw, said sleeve having a length 20 commensurate with that of the screw and adapted when fully engaged therewith to substantially enclose said screw, load supporting means on the sleeve for engagement with an object to be lifted, said load supporting means comprising a ring-

like member rockable on the sleeve from a position in which the ring is freely slideable thereon to an inclined position in which the ring frictionally grips the sleeve, said ring having a lateral projection thereon with upstanding fingers for engagement with an object to be lifted, the axes of the fingers being parallel and inclined with respect to the ring axis, and means for rotating the screw.

15. 4. A jack of the character described comprising an upstanding rotatable lifting screw having an annular groove adjacent the lower end thereof, a housing comprising a ground engaging base having a projection for axial support of the lifting screw, said housing having an opening in the upper portion vertically aligned with said projection for loose reception of the screw, rotatable driving means for the screw journaled on the base projection and operatively engaging the screw, and means on the housing interfitting the screw annular groove to maintain the housing and screw in assembly.

CHARLES J. SMITH.
